STRAP CUTTING TOOL

Norman T. Bissell, Reading, and Norman C. Moore, Haverhill, Mass., assignors to Western Electric Company, Incorporated, New York, N. Y., a corporation of New York

Application September 1, 1945, Serial No. 614,016

5 Claims. (Cl. 30—134)

1

This invention relates to strap cutting tools, and more particularly to tools for cutting metal straps used in binding large packages.

The metal straps employed for binding packages are secured in place under tension. Therefore, due to the inherent resilient nature of such metal straps and the tension therein while binding packages, the ends of the straps when cut will fly outwardly, creating a hazardous condition if nothing is provided to control the ends of the strap immediately after the strap is cut. This condition is also enhanced by increasing the tension in the strap during the positioning of a cutting tool between the strap and the package to bring about the cutting operation.

The principle of the invention is to provide a strap cutting tool which is highly efficient, not only in the cutting of straps, but in controlling the ends thereof adjacent the cut until the tension in the strap diminishes.

In the present embodiment of the invention, the strap cutting tool grips the strap upon each side of the portion to be cut prior to, during and after the cutting operation to hold the ends of the strap against flying outwardly. Specifically the tool includes a wedge-like base for movement between the strap and the package to cooperate with a knife, carried by a pivoted member of the base, to cut through the strap. There are gripping pads pivotally supported to lie upon the strap at each side of the portion to be cut. These gripping pads are to be engaged by spring pressed plungers carried by the pivoted member to cause the pads to cooperate with the base to grip the strap firmly prior to cutting of the strap and to hold the ends of the strap against flying outwardly after the cut has been completed. The pressure applied to the gripping pads during the cutting may be gradually decreased by the movement of the pivoted member away from the base to allow the ends of the strap to gradually move outwardly.

Other objects and advantages will be apparent from the following detailed description when considered in conjunction with the accompanying drawing, wherein

Fig. 1 is a side elevational view of the strap cutting tool shown at the completion of the cutting operation;

Fig. 2 is a fragmentary sectional view of the strap cutting tool, illustrating the completion of a cutting operation; and

Fig. 3 is a perspective view of a package secured by the aid of metal straps.

Referring now to the specific embodiment in

2

the drawing, the illustrations in Figs. 1 and 2 represent the cutting of any of the straps 10 of the package or bale 11. The cutting tool includes a base 12, having a flat under surface 14 to rest upon the package 11 and a tapered surface 15, providing a wedge-like portion which may be moved freely beneath the strap 10, as illustrated particularly in Fig. 2. The base 12 has an upright portion 16 which carries a shaft 10 or pivot 17 for a holder 18. The base also includes portions 19 between which gripping pads 20 are disposed, and to which the rearmost ends of the pads are pivotally secured as at 21. The leading ends of the pads 20 are rounded at 22 so that the gripping pads may ride upon the strap as the tool is moved into place.

The holder 18 is apertured to receive plungers 24 and springs 25, the latter normally forcing the plungers 24 outwardly to engage their respective gripping pads 20 during the pivotal movement of the holder 18 toward the base 12. The force of the springs 25 may be varied by adjustment of their respective screws 26, these adjustments being maintained by lock nuts 27. The holder 18 also carries a knife 28 which is disposed in an aperture 29 of the holder and held in place by the aid of pins 30 and screws 31. A handle 32 is integral with the holder 18 for manual movement of the holder with the knife 28 and the spring pressed plungers. A notch 34 is cut longitudinally in the base 12 to provide one or two cutting edges 35 (only one being shown) to cooperate with the knife in cutting the strap.

During the operation of the cutting tool, the operator may hold the tool in one hand by gripping the handle 32 and moving the tool with respect to the package 11 to cause the leading end of the base, that is, the wedge shaped portion 15 thereof, to pass between the package and the portion of the strap to be cut until that portion of the strap lies over the notch 34 at a position to be engaged by the knife. While in this position, the gripping pads 20 will lie upon the strap, and will be engaged by their plungers 24 in advance of the knife engaging the strap so that a sufficient gripping force on these portions of the strap may be created before the strap is cut. The gripping force is increased during the cutting operation due to the fact that during the pivotal movement of the holder 18 toward the base 12, the springs 25 are compressed, the force created therein being increased to the end of the cutting operation, illustrated in Figs. 1 and 2.

The gripping force is decreased in a similar manner during the opening of the tool, that is, during the movement of the holder 18 about its pivot to move the knife 28 outwardly away from the base. During this operation, or opening of the tool, the holding force of the pads will continue although at a diminishing rate until the knife has been moved away from the strap. In this manner the tension originally placed in the strap and increased by the positioning of the base 12 therebeneath has been allowed to diminish gradually until there is no tension in the strap when the ends are released. Furthermore, the added effect of the resilient nature of the strap is also controlled by the tool, the ends of the cut strap being allowed to fall to their respective sides rather than fly outwardly, causing possible material damage and bodily injury.

Although specific improvements of the invention have been shown and described, it will be understood that they are but illustrative and that various modifications may be made therein without departing from the scope and spirit of this invention as defined by the appended claims. It should also be understood that the tool may be used for cutting strands, such as wire, and materials of other cross-sectional contours although it was primarily designed for cutting metal straps. The term "strand" is, therefore, intended to broadly describe all such materials.

What is claimed is:

1. A tool for cutting package binding straps, the tool comprising a base having a wedge shaped leading end to facilitate movement of the base between a package and a tensioned strap binding the package, a knife to cooperate with the base to cut the strap, a holder for the knife movable relative to the base to move the knife into and out of its cutting position, and means to grip the strap to hold the ends of the strap created by the cut against flying outwardly.

2. A tool for cutting package binding straps, the tool comprising a base having a wedge shaped leading end to facilitate movement of the base between a package and a tensioned strap binding the package, a knife to cooperate with the base to cut the strap, a holder for the knife movable relative to the base to move the knife into and out of its cutting position, gripping pads disposed adjacent the base one upon each side of the cutting position, and means carried by the holder to force the gripping pads into gripping engagement with the straps prior to the cutting of the strap.

3. A tool for cutting package binding straps, the tool comprising a supporting handle, a knife, a holder therefor carried by the handle, a base pivotally carried by the holder and having a cutting edge to cooperate with the knife to cut a tensioned strap, a wedge shaped leading end to facilitate movement of the base between the tensioned strap and a package bound thereby, a gripping pad pivotally carried by the base upon each side of the cutting edge, and resilient means carried by the holder to engage their respective pads in advance of the knife engaging the strap to cause the pads to cooperate with the base to grip the strap prior to, during and after the cutting operation until the tension initially in the strap is spent.

4. A tool for cutting package binding straps, the tool comprising a base having a cutting edge and a wedge shaped leading end to facilitate movement of the base between a package and a tensioned strap binding the package, a knife to cooperate with the cutting edge of the base to cut the strap, a holder for the knife movable relative to the base to move the knife into and out of its cutting position, and means to grip the strap to hold the ends of the strap created by the cut against flying outwardly.

5. A tool for cutting package binding straps, the tool comprising a base having a cutting edge and a wedge shaped leading end to facilitate movement of the base between a package and a tensioned strap binding the package, a knife to cooperate with the cutting edge of the base to cut the strap, a holder for the knife movable relative to the base to move the knife into and out of its cutting position, gripping pads disposed adjacent the base one upon each side of the cutting position, and spring pressed plungers carried by the holder and movable therewith to engage their respective gripping pad and force them into gripping engagement with the strap prior to the cutting of the strap between the pads.
